CLAIM

The ornamental design for a detector for a sewing machine as shown and described.

DESCRIPTION

FIG. 1 is top left perspective view of a detector for a sewing machine showing our new design;

FIG. 2 is top right perspective view of the design of FIG. 1;

FIG. 3 is a front elevational view of the design of FIG. 1;

FIG. 4 is a rear elevational view of the design of FIG. 1;

FIG. 5 is a right side view of the design of FIG. 1;

FIG. 6 is a left side view of the design of FIG. 1;

FIG. 7 is a top plan view of the design of FIG. 1; and,

FIG. 8 is a bottom plan view of the design of FIG. 1.

The broken lines in the drawings illustrate portions of the detector for a sewing machine that form no part of the claimed design.

1 Claim, 8 Drawing Sheets(56)
